UNITED STATES PATENT OFFICE.

CLARENCE E. RUSSELL, OF KIRKWOOD, MISSOURI, ASSIGNOR, BY MESNE ASSIGNMENTS, TO THE CORNO MILLS COMPANY, OF EAST ST. LOUIS, ILLINOIS, A CORPORATION OF ILLINOIS.

CAPPING MACHINE.

Application filed October 15, 1920. Serial No. 417,211.

To all whom it may concern:

Be it known that I, CLARENCE E. RUSSELL, a citizen of the United States of America, and a resident of Kirkwood, in the county 5 of St. Louis and State of Missouri, have invented certain new and useful Improvements in Capping Machines, of which the following is a full, clear, and exact description, reference being had to the accompanying 10 drawings, forming a part of this specification.

This invention relates to improvements in capping machines, one of the objects being to produce a simple automatic machine 15 whereby caps may be positively applied to containers. An object of the invention is to provide a means whereby the caps and cartons are accurately alined with each other during the capping operations.

20 A further object is to produce a machine of this kind adapted to apply flexible paper caps to cartons. In the preferred form of the invention, the cap is frictionally held by a guiding device whereby it is guided 25 onto the carton, and a suitable plunger is used to force the cap along the guiding device. Flexible paper caps of this kind are usually provided with flanges which fit over the cartons, and the invention includes a 30 novel means whereby the flexible flanges are expanded slightly by forcing them onto the friction faces of the guiding device, thereby causing the caps to readily pass onto the containers.

35 With the foregoing and other objects in view, the invention comprises the novel construction, combination and arrangement of parts hereinafter more specifically described and illustrated in the accompanying 40 drawings wherein is shown the preferred embodiment of the invention. However, it is to be understood that the invention comprehends changes, variations and modifications which come within the scope of the 45 claims hereunto appended.

Fig. I is a top or plan view of a capping machine embodying the features of this invention.

Fig. II is a side elevation of the machine.

50 Fig. III is a rear elevation, partly in section.

Fig. IV is a vertical section taken approximately on the line IV—IV, Fig. II.

55 Fig. V is an enlarged detail view showing the convex pressure member whereby

the cap is forced into firm engagement with a guiding device during the capping operation, so as to slightly expand the lower margin of the carton.

Fig. VI is an enlarged fragmentary top 60 view showing the gripping members whereby the cap is alined with the container, and a portion of the means for feeding the caps to said gripping members.

Fig. VII is a vertical section taken approximately on the line VII—VII, Fig. VI.

A designates cylindrical cartons seated on the top of a table 1, and B designates caps arranged in a guideway 2 located above the table. The cartons may be delivered to the 70 table by hand or by any suitable mechanism. The caps are fed to the guideway 2 through the medium of a chute 2', shown in Fig. II.

The device for applying the caps to the 75 cartons includes a pair of gripping members 3 movable toward each other to grip the cap and carton and serving as guides for directing the cap to the carton. Before describing the various elements of the cap- 80 applying device I will point out the means for feeding the caps and cartons to the gripping members 3.

The carton feeder herein shown includes a pair of sprocket chains 4 movable along 85 the top face of the table 1 and connected together by means of rods 5 which engage the cartons to push them along the top of the table. Each sprocket chain 4 passes around a drive wheel 6 near one end of the 90 table and an idle wheel 7' near the other end. The drive wheels 6 are fixed to a shaft 7, and a ratchet wheel 8 is also fixed to this shaft. 9 designates an oscillatory arm (Fig. II) loosely mounted on the shaft 7, and 10 95 designates a pawl pivoted to said arm. A spring 11 retains the pawl 10 in engagement with the ratchet wheel 8. A rotary drive shaft 12 is provided with a disk 13 having a crank pin 14. 15 designates a connecting 100 rod, or link, whereby the crank pin 14 is connected to the pawl carrying arm 9. The drive shaft 12 is driven continuously so as to permit movement from the crank pin 14 to the connecting rod 15, thereby imparting an 105 oscillatory movement to the pawl carrying arm 9. As a consequence, the shaft 7 is driven intermittently through the medium of ratchet 8 and pawl 10. An intermittent movement is thus transmitted to the 110

Fig. V is an enlarged detail view showing the convex pressure member whereby

sprocket chain 4 so as to advance the containers A step by step. These containers, or cartons, are separated from each other, and in response to each operation of the sprocket chain 4, one of the cartons A is removed from the space between the gripping jaws while the next adjacent carton passes into this space.

The means for feeding the caps comprises an endless friction belt 16 passing around an idle wheel 17 and a drive wheel 18, the latter being fixed to a drive shaft 19 which may be driven continuously through the medium of any suitable power mechanism, such, 10 for instance, as a driving belt 19^b operating over a pulley 19^b mounted on said shaft 19 as shown in Fig. I of the drawings. The belt 16 frictionally engages the top face of the caps B, and it tends to move all of the 15 caps toward the gripping jaws 3.

To control the delivery of the caps to the gripping members 3, a stop arm 20 is located at the discharge end of guideway 2, said stop arm being provided with fingers 20' which 20 rest upon the guideway, as shown in Fig. IV. 25 21 designates a pivot whereby the stop arm 20 is secured to a stationary part of the machine. When the stop arm 20 occupies the position shown in the drawings, it prevents 30 displacement of the caps which are frictionally engaged with the moving belt 16, but this arm is intermittently lifted to release the caps, thereby permitting one of the caps to pass into the space between the gripping 35 members 3. The means for actuating the stop arm 20 includes a horizontal finger 22 (Figs. I and IV) fixed to the upper end of a vertical shaft 23 and an operating finger 24 fixed to the lower end of said shaft. 25 designates a torsional spring surrounding the 40 vertical shaft 23 (Fig. IV) and tending to retain the operating finger 24 in engagement with a stop pin 26. The lower end of spring 25 is fixed to the shaft 23 and the upper end 45 is fixed to a stationary part of the machine, as shown in Fig. IV. The operating finger 24 extends into the path of the cartons A, while the finger 22 lies under and engages an inclined face on the stop arm 20.

When the intermittent carton feeder is in motion, the uncapped cartons move toward the gripping members 3 and one of the cartons engages the operating finger 24 (Figs. I and IV). As a result, motion is transmitted from the moving carton to the operating finger 24, and thence through the vertical shaft 23 to the finger 22 which engages the inclined face of stop arm 20 (Fig. IV), thereby lifting the stop arm to release the caps. All of the caps engaged with the friction belt 16 then move forwardly toward the gripping members 3, but when the operating carton passes from the finger 24, the spring 25 restores the fingers 22 and 24 to the positions shown by Figs. I and IV, thereby per-

mitting the stop arm 20 to drop by gravity until its fingers 20' rest upon the top of the cap which has just been released, and shortly thereafter, the stop arm will drop between this cap and the next succeeding cap, so as to 70 again prevent movement of the caps engaged by the friction belt 16. The caps are thus intermittently delivered to the space between the gripping jaws, where they are 75 acted upon as will be presently described.

Each gripping jaw 3 is a semi-cylindrical member conforming to the shape of the cartons and provided with a horizontal extension 27 located in stationary guides 28, as shown by Figs. II, III and IV. To provide for the transmission of movement to these horizontally guided gripping members, each extension 27 is provided with a pin 29 adapted to receive the forked upper end of a lever 30 driven by a cam 31 on the 80 constantly rotating shaft 12. There are two levers 30, one for each of the gripping members 3, and the cams 31 are adapted to cooperate with these levers, as shown by Fig. III, to move the gripping members toward each other. The levers 30 are yieldingly connected together by means of a spring 32 (Fig. III) which tends to force the gripping members 3 away from each other.

After the cap and container have been delivered to the space between the gripping members 3, the latter move toward each other to grip the cap and container, but the cap must be temporarily supported before it is frictionally engaged by the gripping members. E designates cap supporting members in the form of thin sheet metal wings extending from the discharge end of the guideway 2 so as to receive the caps passing from this guideway. Each supporting member E 100 is pivoted at 33 to a stationary part of the machine and provided with a cap-supporting extension 34 adapted to pass through a slot in the gripping member with which it is associated. When the cap is discharged from the guideway 2 to the space between the gripping members 3, the supporting wings E occupy the positions shown by full lines in Figs. I and VI. The cap supporting extension 34 will therefore lie between the 105 cap and the container, so as to temporarily support the cap while the gripping members 3 move toward each other to grip the cap and container. 35 designates links connecting the movable gripping members 3 to the supporting wings E, as shown most clearly by Fig. VI. When the gripping members 3 move toward each other motion is transmitted through the links 35, with the result of moving the supporting wings away 110 from each other, thereby removing the supporting wings from the space between the cap and the container. It will now be understood that the cap is temporarily supported by the members 34, and that these 115 120 125 130

members are shifted to the positions shown by dotted lines in Fig. VI while the gripping members are moving to the positions shown by dotted lines.

5 The semi-cylindrical gripping members 3, conforming to the shape of the cap and carton, serve as means for alining the cap and carton, and they also serve as guides for directing the cap to the carton. It is therefore unnecessary for the carton feeder and cap feeder to accurately aline the cap with the carton. Each of the gripping members is provided with an offset portion 3^a at its upper end, these offset portions being necessary to provide space for the caps to move downwardly within said gripping members while the cartons are firmly gripped by the lower portions of said members 3, so that said caps may be forced onto said cartons.

10 The means for forcing the cap onto the carton comprises a vertically movable plunger rod 36 provided with a head 36' (Fig. V) adapted to engage the top of the cap. An operating lever 37 is provided with a fork 38 (Fig. III) extending into an annular groove in the plunger rod 36. 39 designates a vertically movable operating rod (Fig. III) actuated by a cam 40 on the shaft 12, and provided with a head 41 engaging the operating lever 37. The head 41 is slidably mounted on the upper end of rod 39, and the spring 42 yieldingly retains this head in engagement with a stop pin 43 on rod 39. If any rigid object is located in the path of the plunger head 36' or if for any reason the cap is prevented from moving downwardly with this plunger head, the spring 42 will yield to permit movement of the operating rod 39, without transmitting movement to the lever 37.

The plunger rod 36 is slidably mounted in a stationary guide 44 (Fig. III) containing a restoring spring 45 which engages a shoulder on the rod, so as to elevate said rod in response to a downward movement of the operating rod 39.

As shown in Fig. V, the plunger head 36' is provided with a convex face which engages the top of the cap B. When the gripping members 3 occupy their closed positions, their inner faces frictionally engage the outer face of the flange 46 of the cap B, and the convex face of plunger head 36' engages the top of the cap to force the cap onto the carton A. If the cap is made of paper, or similar flexible material, the pressure transmitted from the convex face of plunger head 36' will tend to expand the lower margin of the cap flange 46, thereby firmly forcing this lower margin into engagement with the friction faces of gripping members 3 and causing the cap to pass freely onto the top of the container. The position of the cap flange 46 is exaggerated in Fig. V, but it will be understood that if this

flange is frictionally engaged with the inner face of gripping members 3, the pressure transmitted from the convex face of plunger head 36' will tend to make the top of the cap conform to this convex face, and this will tend to expand the lower margin of flange 46, so as to more firmly engage this margin with the friction face and at the same time remove wrinkles and other irregularities which would otherwise prevent the cap from passing onto the container. At the beginning of this operation, while the irregular paper cap is frictionally held between the gripping members, it does not conform precisely to the inner face of these members, and its flange is thereafter expanded to remove the irregularities, thereby permitting the cap to pass freely onto the container. Since the external diameter of the cap B is larger than that of the container A, the inner faces of the gripping members are preferably formed with shoulders below the plane of the cap in Fig. V, but these shoulders do not perform any useful function, said shoulders resulting from the presence of the offset portions 3^a.

I claim:

1. In a carton capping machine, gripping members adapted to embrace the cap and carton, a cap support whereby the cap is held between said gripping members, said cap support being movable between the cap and carton, means for closing said gripping members to grip the cap and carton, means for transmitting movement to said cap support to remove the same from the cap while the latter is held by said gripping members, said gripping members having friction faces whereby the cap is yieldingly held above and in alinement with the carton, and means for forcing the cap onto the carton while said friction faces are engaged with the cap.

2. In a carton capping machine, gripping members adapted to embrace the cap and carton, a cap support whereby the cap is held between said gripping members, means for removing said cap support from the cap and at the same time closing said gripping members to grip the cap and carton, said gripping members having friction faces whereby the cap is yieldingly held above and in alinement with the carton, and means for forcing the cap onto the carton while said friction faces are engaged with the cap.

3. In a carton capping machine, gripping members adapted to embrace the cap and carton, a cap support whereby the cap is held between said gripping members, said cap support comprising a pair of seats located in the path of the cap, operating means whereby said gripping members are closed to grip the cap, means for transmitting motion to said pair of seats to displace them from the cap, said gripping members having friction faces whereby the cap is

- yieldingly held in alinement with the carton, and means for forcing the cap onto the carton while said friction faces are engaged with the cap.
6. 4. In a carton capping machine, gripping members adapted to embrace the cap and carton, a cap support whereby the cap is held between said gripping members, said cap support comprising a pair of seats located in the path of the cap, operating means whereby said gripping members are closed to grip the cap, said seats being movable away from each other to release the cap therefrom, operating means connecting said 10 seats to said gripping members so as to move the seats away from the cap while the gripping members move toward each other, said gripping members having friction faces whereby the cap is yieldingly held in alinement with the carton, and means for forcing the cap onto the carton while said friction faces are engaged with the cap.
5. In a carton capping machine, a guiding device whereby the cap is directed to the carton, said guiding device being adapted to engage the cap and carton, a cap support whereby the cap is held above the carton, said cap support being removable from the cap, means, independent of said cap support, whereby caps are successively fed into said guiding device, means whereby cartons are successively fed to a point directly below said cap support, and cap-applying means cooperating with said guiding device 25 to apply the cap to the carton, said cap-applying means being effective while said guiding device is engaged with both the cap and carton.
6. In a carton capping machine, gripping members adapted to embrace a cap and carton, a cap support whereby the cap is held between said gripping members, means whereby caps are successively fed to the top of said cap support, means whereby cartons 30 are successively fed to a point directly below said cap support, means for closing said gripping members to grip the cap and carton, means for transmitting movement from said gripping members to said cap support 35 to remove the same from the cap, said gripping members having friction faces whereby the cap is yieldingly held in alinement with the carton, and means for forcing the cap onto the carton while said friction faces are 40 engaged with the cap.
7. In a machine for applying flexible

flanged caps to cartons, means whereby the flange of the cap is held in alinement with a carton, and cap-applying means including a flange-expanding member having a convex face adapted to engage the top of the flexible cap, said pressure member serving as a spreader for the flange of the cap held by the first mentioned means.

8. In a machine for applying flexible flange caps to cartons, a guiding device having friction faces whereby the flange of the cap is held in alinement with the carton, a cap-applying means including a flange-expanding member having a convex face adapted to engage the top of the flexible cap, said flange-expanding member being effective while the cap flange is engaged with said friction face, so as to serve as a spreader for the cap flange.

9. In a machine for applying flexible flange caps to cartons, gripping members adapted to embrace the cap and carton, means for closing said gripping members to grip the cap and carton, said gripping members having friction faces whereby the cap is yieldingly held in alinement with the carton, and flange-expanding means for forcing the cap onto the carton while the flange of the cap is engaged with said friction face, the last mentioned means including a pressure member having a convex face adapted to engage the top of the flexible cap, so as to force the lower margin of the cap flange into firm engagement with said friction face.

10. In a machine for applying flexible flange caps to cylindrical cartons, semi-cylindrical gripping members adapted to embrace the cap and carton, means for closing said semi-cylindrical gripping members to grip the cap and carton, said gripping members having friction faces whereby the flange of the cap is yieldingly held in alinement with but above the cylindrical carton, and flange-expanding means for forcing the cap onto the carton while said friction faces are engaged with the cap flange, the last mentioned means including a plunger whereby the cap is forced along said friction faces, and said plunger having a convex face engaging the central portion of the flexible cap, so as to force the cap flange into firm engagement with said friction faces.

In testimony that I claim the foregoing I hereunto affix my signature.

CLARENCE E. RUSSELL.
